UNITED STATES PATENT OFFICE.

ALFRED WATERS PROCTOR, OF NEW YORK, N. Y.

CHECK-PUNCH.

No. 824,814.

Specification of Letters Patent.

Patented July 3, 1906.

Application filed January 23, 1906. Serial No. 297,419.

To all whom it may concern:

Be it known that I, ALFRED WATERS PROCTOR, a citizen of the United States, residing at New York, in the county of New York and State of New York, have invented certain new and useful Improvements in Check-Punches, of which the following is a full, clear, and exact description.

My invention relates to check-punches, and particularly to that class in which the check is impressed with an inscription to indicate a limit for that particular draft or paper. This is commonly accomplished by impressing the words "Not over twenty dollars," or "Not over one hundred dollars," or other amount indicating a fixed limit of value, and thus prevent loss by the "raising" of the check or other fraudulent practices.

The principal object of my invention is to provide a pocket device of the above character of maximum cheapness and simplicity and having an attractive appearance.

With this and other objects in view my invention consists in the construction, combination, location, and arrangement of parts hereinafter set forth and shown and finally particularly pointed out in the appended claims.

In the drawings, Figure 1 is a perspective view of a check-punch embodying the principles of my invention. Fig. 2 is a side view of the same. Fig. 3 is a section on the line III-III of Fig. 2.

In carrying out my invention I make use of some resilient sheet material which is folded over, so as to produce two parallel leaves or layers, and I emboss these with the desired inscription, so that they will likewise emboss a sheet of paper when it is pressed between them. I then provide a backing for each of the layers or leaves directly behind the inscription on each, so as to make the structure more rigid, and provide a convenient point of engagement for the fingers when the device is used.

Referring to the drawings, 1 denotes a strip which I make of springy tinned sheet-steel

bent into a U shape, with a rounded rear edge 2 and channels or grooves 3 at each end or extremity. The channels preferably have a rectangular section, as shown in Fig. 2. Simultaneously with the formation of the channels in the usual die-press I emboss the bottom or face 4 of each with male and female impressions, denoting the inscription desired. This is a convenient method of manufacture; but I do not, of course, desire to be limited or restricted to any particular method of production of the check-punch.

5 designates painted wooden blocks of an attractive hue inserted into the channels or grooves 3 to stiffen the construction and provide a point of engagement for the fingers. Any desired rigid backing could of course be used.

65 What I claim is—

1. A check-punch comprising a U-shaped sheet-metal strip having a male and female inscription in opposed relation on its extremities, and means for stiffening said extremities.

2. A check-punch comprising a strip formed with opposed leaves or layers having male and female inscriptions embossed thereon, and rigid means for backing said inscriptions throughout their length.

3. A check-punch comprising a strip formed with opposed leaves or layers with male and female inscriptions embossed thereon and having grooves or channels, and stiffening means in said channels.

4. A check-punch comprising a U-shaped strip having grooves or channels formed at its extremities, the faces or bottoms of which are embossed to form inscriptions, and blocks adapted to back said inscriptions, and contained in said grooves.

In witness whereof I subscribe my signature in the presence of two witnesses.

ALFRED WATERS PROCTOR.
